His Attorney

UNITED STATES PATENT OFFICE

JOHN C. READ, OF RUGBY, ENGLAND, ASSIGNOR TO GENERAL ELECTRIC COMPANY, A CORPORATION OF NEW YORK

VAPOR DISCHARGE DEVICE

Application filed January 18, 1929, Serial No. 333,261, and in Great Britain February 16, 1928.

My invention relates to vapor discharge devices such as mercury arc rectifiers for example, and has for its principal object the provision of an improved means whereby the 5 vacuum chamber of the device may be effectively evacuated during operation.

In mercury arc rectifiers, if the connecting pipe leading from the vacuum chamber to the evacuating pump is placed at the centre of the chamber, then there is risk that air may be trapped in the corners of the chamber near the anodes; and if the pipe is placed near the anodes air is trapped at the centre of the tank; since in both cases the violent 15 blast of mercury vapor issuing from the cathode during operation tends to drive air before it into the various pockets in the chamber, and thereby prevent it from being evacuated by the pump. It is undesirable to 20 provide several pipes from the vacuum chamber to the pump to eliminate this trouble, on account of the complication and difficulty of making vacuum-tight joints.

The present invention consists in connecting the evacuating pipe of the vacuum pump to the vacuum chamber at any convenient point and providing pipes inside the vacuum chamber leading from any other parts of it where air may collect, to this evacuating 30 pipe.

The invention is illustrated diagrammatically in the accompanying drawing. In this, 1 is the vacuum chamber of a mercury arc rectifier, whose cathode is mounted at 2 and anodes at 3 and 4 respectively. The pipe 5 leading to the vacuum pump is shown at the centre of the vacuum chamber. It is found that with this position of the evacuating pipe there is sometimes a tendency for air to be 40 trapped by the mercury vapor blast at the rim 6 of the tank and this cannot be prevented by attaching the evacuating pipe at 6 because in that case air is sometimes trapped in the centre of the tank instead. Internal ducts or pipes 7 are therefore provided leading to the pipe 5 from points where air may be expected to be trapped.

In this way air is drained away from any 50 pockets in the vacuum chamber without being influenced by the blast of mercury vapor,

and at the same time, since these drain pipes are entirely inside the vacuum chamber, no additional vacuum-tight joints are required.

In arranging such internal air drain ducts it is desirable to make the coolest part of the 55 duct be the end which is adjacent to the evacuating pipe. This insures that any flow of mercury vapor which takes place along the duct will be in the direction to help the air flow to pipe 5 rather than in a direction to 60 hinder it. One way of taking care of this requirement is to cool the evacuating pipe 5 by a cooling jacket 8 and to cause the ducts 7 to extend up a short distance into the cooled 65 pipe 5.

The invention is not limited to the particular shape of vacuum chamber shown but may be applied in any shape of vacuum chamber to drain the air away from any pockets where it might be expected to collect.

What I claim as new and desire to secure by Letters Patent of the United States is:

1. A vapor discharge device including an evacuated vessel, an exhaust pipe attached thereto and opening into the upper portion 75 of said vessel to drain air from said portion, and a second pipe located within said vessel extending into the end of said exhaust pipe from another point within said vessel to drain air into said exhaust pipe from another 80 portion of said vessel.

2. A vapor discharge device including an evacuated vessel, an exhaust pipe attached thereto and opening into the upper portion 85 of said vessel to drain air from said portion, and a plurality of ducts within said vessel opening into the end of said pipe and leading from said pipe to separate points within said vessel to drain air into said exhaust pipe from other portions of said vessel. 90

3. A vapor discharge device including an evacuated vessel, an exhaust pipe attached thereto, a plurality of pipes extending from separate points within said vessel into the end of said pipe, and means for cooling said 95 evacuating pipe.

4. A vapor discharge device including an evacuated vessel provided with anode chambers, an exhaust pipe attached to said vessel, and means for evacuating said anode cham- 100

bers including a plurality of pipes within said vessel and extending from said anode chambers into the mouth of said exhausting pipe.

5. A vapor discharge device including an evacuated vessel, an exhaust pipe attached thereto, and a plurality of ducts within said vessel leading from separate points therein and extending into the end of said exhaust

10 pipe.

6. A vapor discharge device including an evacuated vessel, an exhaust pipe attached to said vessel, and a plurality of pipes mounted within said vessel and leading respectively

15 to said exhaust pipe from points within said vessel at which air tends to collect.

7. A vapor discharge device including an evacuated vessel, an exhaust pipe attached to said vessel at a point at which air tends

20 to collect, and a plurality of ducts within said vessel and leading respectively to said exhaust pipe from other points within said vessel at which air tends to be trapped, to

25 cause said trapped air to be evacuated by said exhaust pipe.

In witness whereof, I hereunto set my hand, this 1st day of January, 1929.

JOHN C. READ.
